[57] CLAIM

The ornamental design for a radio modem docking station for palm-sized computer, as shown and described.

DESCRIPTION

FIG. 1 is a perspective view of the radio modem docking station for palm-sized computer showing my new design;
FIG. 2 is a top plan view thereof;
FIG. 3 is a front elevational view thereof;
FIG. 4 is a rear elevational view thereof;
FIG. 5 is left side elevational view thereof;
FIG. 6 is a right side elevational view thereof; and,
FIG. 7 is a bottom plan view thereof.

The broken lines are shown in FIG. 5 for illustrative purposes only and form no part of the claimed design.
